UNITED STATES PATENT OFFICE.

JOSEPHINE WERNER, OF BALTIMORE, MARYLAND.

CURTAIN-FIXTURE.

1,027,950.

Specification of Letters Patent.

Patented May 28, 1912.

Application filed February 15, 1912. Serial No. 677,662.

To all whom it may concern:

Be it known that I, JOSEPHINE WERNER, a citizen of the United States, residing at Baltimore, in the State of Maryland, have 5 invented certain new and useful Improvements in Curtain-Fixtures; and I do hereby declare the following to be a full, clear, and exact description of the invention, such as will enable others skilled in the art to which

10 it appertains to make and use the same.

My invention relates to curtain fixtures and more particularly to that variety wherein pins, rings and other special securing devices are wholly dispensed with and my 15 prime object is to provide a curtain supporting appliance which will be found to be thoroughly reliable and efficient in holding the curtain or curtains in an adjusted position and whereby the curtains may be very 20 quickly removed and replaced at pleasure with a minimum amount of labor.

Other objects and advantages will be hereinafter clearly set forth, pointed out in 25 the claim and illustrated in the accompanying drawings in which,

Figure 1 shows my invention complete as applied to use. Fig. 2 shows an end section of my curtain securing appliance in its operative position and ready for engagement 30 with the curtain. Fig. 3 shows a view of the opposite end of my curtain supporting appliance from that illustrated in Fig. 2. Fig. 4 is a sectional view of my curtain supporting appliance. Fig. 5 is a detail view showing a longitudinal section of a portion of my curtain holding appliance. Fig. 6 is a perspective detail view of the free end of my curtain holding member, and, Fig. 7 shows a detail of an employed or different form 35 of construction of the central anchoring rib or member.

For convenience of reference to the various details of my invention and coöperating accessories numerals will be employed, the 45 same numeral applying to a corresponding part in the several views.

In materializing my invention I provide any suitable form of body portion or housing as indicated by the numeral 1 which in 50 this instance may be very readily and cheaply formed of suitable material and is adapted to be secured in position upon the top of the window, door opening or the like where it is desired that curtains are to be 55 mounted. At one end of the housing 1, I secure in any preferred way as by the hinges

2, the cross head 3 to which I permanently secure in any preferred manner a pair of parallel bars or rods 4 of any suitable material while to the opposite ends of said rods 60 or parallel members I secure the cross head 5 which has upon its outer side any suitable form of catch or staple 6 designed to co-operate with the securing member 7 properly connected in position upon the end of the 65 housing 1, as indicated by the numeral 8. The member 7 is provided with a slot to receive the staple 6 which latter projects through said slot and is adapted to receive the hook 9 carried by the chain 10, as clearly 70 shown in Figs. 1 and 2 of the drawings. The chain is of sufficient length to permit the parallel rod sections to hang downward sufficiently below the housing as indicated by the dotted lines in Fig. 1 to readily permit the curtain to be placed over the same when by directing upward the free end of 75 said parallel rods and securing said end as by the member 7, the curtains will be securely held in their adjusted positions upon 80 said parallel members inasmuch as they are forced upward of either side of the rib or bar 11 carried by the housing and permanently secured thereto in such a position that the lower tapered edge thereof will fit 85 tightly between the said members 4, as clearly shown in Fig. 4 of the drawings.

In some instances I provide upon the lower edge of the member 11 a plurality of points 12 to frictionally engage the curtain 90 whereby they will be more reliably held against casually slipping out of an adjusted position. I reserve the right however, to wholly dispense with the points 12 in which case the tapered edge of the member 11 will 95 be left wholly smooth for wedging tightly between the members 4 and thereby preventing the curtain from moving out of an adjusted position.

It will thus be seen that I have provided 100 a thoroughly reliable and efficient securing appliance for holding window curtains, portières and the like in an adjusted position and at the same time most readily permitting the curtains to be removed as when 105 it is desired to clean the same or for other purposes and while I have described the preferred construction and combination of parts I desire to comprehend such substantial equivalents thereof as may be considered as falling fairly in the scope of my 110 invention.

What I claim is:—

The herein described curtain securing appliance comprising a suitable housing, a rib section rigidly secured to and carried by said housing, a movable member comprising a pair of parallel bars adapted to fit snugly on either side of said member, suitable means to pivotally connect said bars to the housing, and additional means to removably

secure and release the opposite end of said bars.

In testimony whereof I have signed my name to this specification in the presence of two subscribing witnesses.

JOSEPHINE WERNER.
